Patented Oct. 10, 1922.

UNITED STATES PATENT OFFICE

FLOYD J. TEFFT, OF CHICAGO, ILLINOIS.

TOWEL HOLDER.

Application filed May 5, 1921. Serial No. 467,183.

To all whom it may concern:

Be it known that I, FLOYD J. TEFFT, a citizen of the United States, residing at Chicago, in the county of Cook and State of Illinois, have invented certain new and useful Improvements in Towel Holders, of which the following is a specification, reference being had therein to the accompanying drawings.

10 This invention relates to towel holders and has for an object to provide a holder for individual towels whereby the towels are in position for convenient use and are properly stored both before and after use in separate receptacles.

15 A further object of the invention is to provide a structure adapted to be located in the wash room or elsewhere as convenience may make necessary, having improved means 20 for holding a plurality of individual towels in position to be withdrawn one at a time, and to be used while still retained upon the device and after use to be dropped into a receptacle without at any time being removed from the structure whereby theft 25 and displacement of towels is prevented.

With these and other objects in view, the invention comprises certain novel units, parts, elements, combinations, arrangements 30 and functions as will be hereinafter more fully described and claimed.

In the drawings:

Figure 1 is a perspective view of the device installed in a conventional wash room.

35 Figure 2 is a view in side elevation showing the manner of attaching the holding rod and keeper to a bar or backing.

Figure 3 is a view in rear elevation showing the locking or attaching means.

40 Figure 4 is a sectional view showing the means of attaching the rod to the ultimate receptacle.

Like characters of reference indicate corresponding parts throughout the several 45 views.

It is well known that in public wash rooms and other places it is considered desirable to furnish individual towels for the individual users. It has been found, however, that the individual towels, which are of small size, are easily carried away, misplaced or otherwise lost and that the cost of upkeep because thereof is considerable. The present invention comprises a rod 10 which is secured to an upright 11 which may be

a bar or the wall as found desirable. The size and proportion of the rod 10 and its location are such as to make it convenient to use a towel, several of which are indicated at 12, while still retained upon the rod by means of loops or rings 13. A receptacle 14 is provided at the lower end of the rod and to which the rod is secured in any approved manner as by the nut 15 into which the towels drop by their own weight when released. To retain the towels in position to be employed and to permit the withdrawal of a single towel at a time, a keeper is employed comprising arms 16 secured to the upright 11 in any approved manner as by the clip 17. The arms 16 are turned upwardly as indicated at 18, forming a constricted passageway between the upturned members at 19. For the purpose of providing a surface wide enough to properly support the towels the arms which are preferably composed of wire are bent outwardly as at 20 so that the adjacent members will properly support the bunch of towels indicated at 12 at the rear of said keeper.

As it is necessary to replace and displace, replacement facilities are provided in a sliding keeper 21, having a keyhole slot 22 proportioned to fit over a head 23 on the extremity of the rod 10. A staple 24 is secured at the rear of the upright 10 proportioned to be inserted through a slot in said keeper 21 and, when found necessary, to receive a padlock 25. At the lower end the rod 10 as has heretofore been mentioned is secured to the receptacle 14 in any approved manner as by the nut 15. To replace towels upon the rod, therefore, the upper end is liberated by manipulating the keeper 21, permitting towels to be strung upon the rod 10 in any number found desirable or necessary to occupy the position shown at Figure 1. After the towels have been used one by one and dropped into the receptacle, they may be removed for laundering by liberating the nut 15 and lifting the rod 10 out of the accumulated towels within the receptacle whereupon such accumulation of towels may be removed. It is also obvious that it will be unnecessary to remove the rod 10 from the receptacle 14 as it will be possible, if the receptacle 14 is movable, to insert the entire structure when the top of the rod 10 has been released and slide the soiled

towels downwardly along the thus inverted rod to be discharged at the then lower end which is normally the upper end.

It will be perfectly apparent that in the use of the towels the foremost of the bunch of towels shown at 12 will be manually withdrawn through the constricted slot 10, the members 16 and 18 yielding for the purpose of permitting the withdrawal of a towel but preventing the passage of more than the 10 towel to which force is applied. The towel will be used while still retained upon the rod 10 after passing by the keeper as has been explained, after which using simply releasing the towel will permit it to drop by its own weight into the receptacle where it is retained for future use and out of sight, presenting a sanitary and artistic appearance.

20. What I claim is:

1. A towel holder comprising a rod having a substantially horizontal portion with an outwardly extending bent portion communicating therewith, means to connect the horizontal portion with a body, a frame comprising a rod secured at its middle beneath the horizontal portion and bent outwardly to form three sides of a rectangle and upwardly to convergence, forming at such convergence a constricted opening, the members of which are then bent outwardly and downwardly to form a frame at the rear

of which a plurality of towels are maintained suspended from the horizontal portion of the rod and between which said towels may be withdrawn by the yielding of the parts, and a receptacle at the lower end of the rod for receiving the towels sliding thereon.

2. A towel holder comprising a receptacle, an elevated support, a rod extending and inclined continuously downward from the support into the receptacle and embodying an intermediate approximately horizontal portion, a frame comprising a rod secured at its middle to the support beneath the horizontal portion and bent outwardly to form three sides of a rectangle and upwardly to convergence, forming at such convergence a constricted opening, the members of which are then bent outwardly and downwardly to form a frame at the rear of which a plurality of towels are maintained suspended from the approximately horizontal portion of the rod and between which said towels may be withdrawn by the yielding of the parts and deposited in the receptacle.

In testimony whereof I hereunto affix my signature in presence of two witnesses.

FLOYD J. TEFFT.
